(57) **CLAIM**

The ornamental design for a cutting board, as shown and described.

DESCRIPTION

FIG. 1 is a perspective view of the cutting board.

FIG. 2 is a front elevational view of the cutting board.

FIG. 3 is a rear elevational view of the cutting board.

FIG. 4 is a left side elevational view of the cutting board.

FIG. 5 is a right side elevational view of the cutting board.

FIG. 6 is a top plan view of the cutting board; and,

FIG. 7 is a bottom plan view of the cutting board.

The broken lines are shown for the purpose of illustrating parts of the article that form no part of the claimed design.

1 Claim, 5 Drawing Sheets
